INVENTOR-

Earl T. Childs,

By *C. E. Murphy*
ATTORNEY.

UNITED STATES PATENT OFFICE.

EARL T. CHILDS, OF AKRON, OHIO.

CLASP.

1,151,084.

Specification of Letters Patent. Patented Aug. 24, 1915.

Application filed November 14, 1914. Serial No. 872,109.

To all whom it may concern:

Be it known that I, EARL T. CHILDS, a citizen of the United States, residing at Akron, in the county of Summit and State of Ohio, have invented new and useful Improvements 5 in Clasps, of which the following is a specification.

This invention relates to improvements in 10 clasps for holding such articles as brooms, milk bottles and the like, and the object thereof is to provide a simple and efficient clasp whereby such articles as brooms, milk bottles, umbrellas, canes, billiard cues, may 15 be suspended and temporarily supported in such a manner that they may be easily removed and replaced from engagement with the clasp.

A further object is to provide a clasp of 20 the type referred to which will be simple, cheaply made, efficient in operation and possessing great durability.

With the foregoing and other objects in 25 view, the invention consists in the novel construction, combination and arrangement of parts constituting the invention to be hereinafter specifically described and illustrated in the accompanying drawings which form a part hereof wherein is shown the preferred embodiment of the invention, but it is to be 30 understood that changes, variations and modifications can be resorted to which come within the scope of the matter hereinafter claimed.

In the drawings in which similar reference numerals indicate like parts in the different figures, Figure 1, is a perspective view 35 of a device embodying this invention looking at one side thereof; and, Fig. 2, is a similar view looking at the opposite side.

The device is preferably constructed of 40 sheet metal possessing a relatively high degree of elasticity so as to be capable of returning to its normal conformation after repeated distortions due to use.

The device embodies a pair of approximately 45 similar members 1 and 2 each of which consists of a strip of sheet metal bent to provide a support-engaging portion 3 provided with an aperture 4 through which 50 may be passed a hold-fast device for securing it to a supporting medium. Each of the members is provided with a portion 5 bent at an acute angle to the portion 3 and when the device is assembled the inner portions of 55 the members 5 are in a substantially contacting relation with respect to each other

near the laterally-bent or support-engaging portions 3. In view of the fact that the portions 5 are formed at acute angles with respect to the portions 3, their outer ends are 60 inclined away from each other but their inner ends are preferably united by some means such for instance, as rivets 6 which are positioned adjacent to the angles between the portions 5 and the support-engaging 65 portions 3, whereby the inner parts of the portions 5 are united together with their outer portions inclined away from each other.

Adapted to inclose the portions 5 is a 70 keeper 7, capable of being slid lengthwise of the members 5 and when slid away from the portions 3 adapted to draw the outer ends of the members 5 toward each other into snug engagement. Extending outwardly 75 and integral with the portions 5 are outwardly-curved portions 8, with their outer ends 9 bent inwardly toward each other and then outwardly-flared at 10 so as to present outwardly-flaring side walls for the reception 80 of the articles to be supported by the device. One of the portions 8 is provided with an inwardly-extending spring tongue 11 formed integral with the member 8 adapted to frictionally hold an object supported by the device.

In operation some object such for instance, as a broom handle or a milk bottle, is forced against the divergent ends 10, causing them to separate to permit the article 90 to be positioned in the opening formed by the portions 8 and be securely held thereby. In doing which the inwardly-extending spring tongue 11 engages the object for securely holding it not only against rotation but against movement longitudinally 95 of the axis of the opening formed by the portions 8. In case the object to be supported is smaller than can be efficiently and effectively grasped by the portions 8, the member 7 is shifted outwardly toward the convexed portions 8, thereby bringing the ends of the portions 5 near to one another and reducing the normal diameter of the opening formed by the portions 8 so that 100 the device is to a certain extent adjustable within certain limits in order to render it capable of adaption to objects of different diameters.

The provision of the inwardly-extending 110 tongue 11 renders the device peculiarly efficient in gripping and holding an object

from movement longitudinally, the tongue 11 yielding under excessive pressure due to the size of the object, while retaining sufficient frictional engagement with the object to effectually hold it against movement in the opening, while, at the same time, the provision of the shiftable member 7 enables a device of a predetermined size capable of being changed to permit it to perform its function of supporting objects of different diameters within reasonable limits.

I claim:—

A device of the character described comprising a pair of members having apertured support-engaging portions arranged in the same plane and extending in opposite directions from each other, each of said portions provided with outwardly-projecting extensions arranged at approximately right angles to said first portion and with the ends thereof adjacent to said first portions united together, the outer parts of the projecting

portions outwardly-inclined away from each other, said inclined portions provided with outwardly convexed fingers having outwardly-flared separated terminals, one of the convexed fingers provided with an integral inwardly-projecting spring tongue extending longitudinally of said finger, the normal tendency of which is to project into the space inclosed by said fingers and arranged to frictionally engage an object supported by said fingers, and a loop-shaped keeper shiftable mounted on the inclined portions of said members and adapted to change the normal position of the flared terminals thereof.

In testimony whereof I have hereunto set my hand in presence of two subscribing witnesses.

EARL T. CHILDS.
